UNITED STATES PATENT OFFICE.

WILLIAM J. TAYLOR, OF CHESTER, ASSIGNOR TO THE TAYLOR GAS PRODUCER COMPANY, OF CAMDEN, NEW JERSEY.

ROTARY BOTTOM OR GRATE APPLICABLE TO FURNACES, &c.

SPECIFICATION forming part of Letters Patent No. 399,797, dated March 19, 1889.

Application filed February 4, 1888. Serial No. 262,975. (No model.)

To all whom it may concern:

Be it known that I, WILLIAM J. TAYLOR, a citizen of the United States, residing at Chester, in the county of Morris and State of New Jersey, have invented certain new and useful Improvements in Rotary Bottoms or Grates Applicable to Furnaces, &c., of which the following is a specification.

My invention relates to improvements in the construction of a bottom or grate applicable more particularly to furnaces for gasifying fuel for making heating - gas or converting solid fuel into gaseous fuel, and such as is generally designated as a "gas-producer." The principal object of my invention is to provide a bottom or grate of comparatively simple construction for supporting the fuel, and with means connected therewith for permitting of the free passage and discharge of a volume of air or steam and air by forced or natural draft directly into the combustion-chamber of the producer, and the grate or bottom actuated by simple mechanical means, whereby all ashes, clinker, or other non-combustible matter may be readily and effectually discharged either intermittently or continuously therefrom over the outer periphery of the bottom while the producer is in full operation and without the slightest interference therewith.

The nature, together with the characteristic features, of my invention will be more fully understood by reference to the accompanying drawing, which shows a vertical central section through a portion of a gas-generating furnace of my improved construction, with the improved rotary grate or bottom therein, and the means connected therewith for admitting and discharging the air or steam and air directly into the combustion-chamber of the furnace.

Referring to the drawing for a further description of the invention, A is a brick foundation for supporting the producer.

B is a cylindrical metal casing supported on the foundation A and constituting a chamber into which the non-combustible material is discharged from the combustion-chamber of the producer. In this casing is provided a door, b, in order that access may be had to

said chamber for removing the accumulating non-combustible material therefrom.

C is an annular plate with a flange or rim around the outer periphery thereof, and this plate is mounted on the casing B of the ash-chamber.

D is the main shell or casing supported on the plate C.

E is a cylindrical metal casing mounted on the plate C, but separated from the main casing or shell D by means of a rectangular-shaped bar, e, and the space between the casing E and the surrounding shell D forms the chamber f. Into this chamber f water is admitted by means of a pipe, f', having a stop-cock, f², and near the top of the main shell D (not shown) may be provided an overflow-pipe and cock.

G is a sight-aperture in the metal plate having a removable cover, g, and which is provided for the purpose of making an examination of the ash-chamber for whatever purpose may be desired.

H and H' are peep-holes arranged at suitable distances apart in the main shell and extending through the casing E of the combustion-chamber, with removable stoppers h and h'. These peep-holes are provided for the purpose of readily ascertaining the dividing-lines between the ash and the more or less incandescent fuel, whereby the attendant in charge may determine with accuracy when to grind down the accumulating non-combustible material over the periphery of the supporting-bottom, to be presently fully described, and in order that the best and most economical results in the making of gas may always be insured.

I and I' are eyes depending from the metal plate C for the reception of agitating-bars i and i', introduced through the casing B and the eyes I and I' for causing the non-combustible material supported upon the bottom when the same is rotated to be discharged more rapidly in one place or part than another over the outer periphery of the bottom, as hereinafter more fully described.

In the brick foundation A is mounted a horizontally-located blast-pipe, J, having an elbow, j, suitably secured thereto, and to the

upper portion of the elbow j is fitted a nipple, j' . Into the foundation A is mounted a metallic base-plate, j^2 , with a central opening therein, and on this plate is mounted a cap-plate, j^3 , secured thereto by means of bolts j^4 . The cap-plate j^3 is preferably provided with a screw-threaded opening, to which the vertical section of the blast-pipe J is secured. The vertical blast-pipe J has mounted thereon a collar, j^6 , held to place by means of a set-screw, j^7 . Around the vertical pipe J is fitted, in any suitable manner, a sleeve, J' , having an annular flange or plate, j^8 , formed, preferably, integral therewith, and this sleeve held in proper position on said pipe by means of the collar j^6 . The sleeve J' extends upward into the combustion-chamber E of the furnace, and this pipe is provided with a deflecting-hood, k , held a suitable distance from the sleeve J' by means of bars k' , secured to the interior surface of said hood k and sleeve J' . This deflecting-hood k has an annular opening in the top thereof, and above the same, at a suitable distance therefrom, is located a cap, l , held in position by means of bars l' . M is a circular solid bottom, either with or without a narrow rim around the outer periphery thereof, and which bottom is secured by means of bolts m and nuts m' to a flange, j^9 , formed, preferably, integral with the sleeve J' . On the under side of the bottom M is provided a rack, m^2 , and with this rack meshes a cog-wheel, n , mounted on a horizontal shaft, o . This shaft o is held in bearings in a bar, p , secured into the casing B and extending

horizontally across the ash-chamber. To the outer extremity of the shaft o is attached a crank, r , for actuating the same and thereby imparting a rotary motion by means of the cog-wheel n to the bottom M for discharging the non-combustible material supported thereon over the outer periphery thereof into the sealed ash-chamber beneath, while the making of gas is uninterruptedly going on. 45

In an application for a patent filed by me under date of February 13, 1888, and serially numbered 263,818, I have shown and described a supporting-bottom of the type illustrated in my present application; but in that case 50 the invention relates to the art of converting solid fuel into gaseous fuel, and hence such bottom has not been claimed therein.

Having thus described the nature and objects of my invention, what I claim as new, 55 and desire to secure by Letters Patent, is—

In a gas-producer, the combination of a vertical blast-pipe, a collar held to place on said pipe, a sleeve encircling said pipe and having a flange, a solid bottom rigidly secured to the 60 flange of said sleeve, and means, as described, for rotating said bottom to cause non-combustible material supported on said bottom to be discharged over the periphery thereof, substantially as shown and described. 65

In witness whereof I have hereunto set my signature in presence of two subscribing witnesses.

WM. J. TAYLOR.
